To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

- 10 The leading features of this design consist of an ornamental panel containing a vase ornament in the center filled with flowers and leaves and supported upon a large fleur-de-lis-shaped ornament, a festoon of flowers suspended from each side of the vase of flowers and from ornamental scrolls forming the sides of the panel, and a small spray of flowers hanging from said scrolls above the festoons, as represented in the accompanying drawing.
- 15 20 The ornamental scrolls forming the adjacent sides of two panels are connected by fleur-

de-lis-shaped ornaments, and above and below these ornaments in each side panel, formed between the connected ornamental scrolls of the main panels, is arranged a vase ornament 25 filled with flowers and leaves, and on each side of said vase ornament are scroll ornaments with sprays of flowers and leaves, which form part of this design.

The design is printed in any desired color 30 or colors or in gilt or bronze and colors on tinted paper of any desired color.

What I claim is—
